By G. L. Gragg Atty.

UNITED STATES PATENT OFFICE.

ERNEST E. YAXLEY, OF CHICAGO, ILLINOIS; LEONA C. YAXLEY ADMINISTRATRIX OF
SAID ERNEST E. YAXLEY, DECEASED.

ELECTROMAGNET.

Application filed May 6, 1927. Serial No. 189,335.

My invention relates to electro-magnets having armatures in swinging connection with supports that are formed of magnetizable material and are included in the same 5 magnetic circuits with the armatures and magnet cores. The invention has for its object an improvement in the joint between the armature and its magnetizable support. One of these two elements, preferably the armature, has a pin formation made integrally therewith and the other one of these two elements has an opening or recess receiving this pin formation whereby the swinging connection of the armature with its support is 10 established. By thus making the pin formation integral with the part that carries it, there is no gap between the pin and the part carrying it to increase the reluctance of the magnetic circuit at this point. To further 15 avoid increasing the reluctance of the magnetic circuit at the pin, the support is formed with an arcuate surface upon which the armature bears and turns.

The invention will be more fully explained 20 in connection with the accompanying drawing in which Fig. 1 is a side elevation of an electro-magnet made in accordance with the preferred embodiment of the invention; Fig. 2 is a side view of the structure shown 25 in Fig. 1; Fig. 3 is a plan view; Fig. 4 is a perspective view showing cooperating parts in separated relation; and Fig. 5 is a sectional view on line 5—5 of Fig. 3 on a larger scale.

The magnet illustrated includes an energizing 30 winding 1 wound about a cylindrical magnetizable core 2 and confined in a winding space defined by the head pieces 3, 4, of insulation. An L shaped bracket 5 is assembled with the core 2 by a nut 6 which is screwed up- 35 on the reduced lower end of said core that is passed through the bracket, said nut clamping the bracket against the unreduced part of the core. The bracket is continued along- 40 side of the magnet winding and terminates in the region of the armature 7 which is mount- 45 ed to swing at the other end of the core. The bracket 5 as well as the armature 7 and core 2 are made of magnetizable material and are included in the same magnetic circuit that 50 contains an air gap between the armature and core. This gap is nearly closed when the

armature is fully attracted upon energization of the magnet. The extent to which the armature may be swung away from the core 2 is limited by hook 8 carried by the armature and terminating just below the head piece 3. The armature 7 is shown as carrying a leaf spring 9 adapted to engage a contact 10, at the front end of the armature, when the armature is retracted by the spring 11 55 which places the armature in an idle or retracted position when the magnet is deenergized. Said spring is anchored, at one end, to a post 12 carried by the bracket 5 and is attached, at its other end, to the stem of a T 60 piece 13, the stem of this piece passing through an opening formed through the rear end of the armature, the head of this piece 65 engaging the armature.

The armature bears and turns upon the con- 70 vex arcuate surface 14 of an armature supporting angular bracket plate 15. This plate is of magnetizable material and is clamped upon and directly against the upper end of bracket 5 by the iron screws 16.

Pins 17 are formed by punching the armature from the outermost broad face of the armature to project from the broad face that is adjacent the core 2, these pins thus being of the same magnetizable material as the armature and integrally formed therewith, whereby there are no reluctance effecting gaps or joints between the armature and these pins. The pins are freely received in openings or recesses 18 formed through the arcuate por- 80 tion of the angular bracket plate 15. The spring 11 holds the armature upon its curved seat 14, but to further insure the retention of the pins in the recesses 18 a guarding plate 19, preferably of brass, is clamped between 85 the plate 15 and the heads of screws 16, this guarding plate having an angular extension 20 which overlies the armature and is suffi- 90 ciently close thereto to prevent the pins from rising clear of the armature bearing 18.

Having thus described my invention, I claim:

An electro-magnet including an energizing winding; an armature; a support for the armature formed of magnetizable material and 100 included in the magnetic circuit of the mag- net, said armature having a pin formation,

said support having a convex arcuate surface which is engaged by the armature in the region of the pin formation, there being a recess in said support that receives said pin formation, to permit the armature to rock upon said arcuate surface; and a guard carried by the support and in lapping relation to the armature in the region of the support and sufficiently close to the armature to maintain the armature upon the support. ¹⁰

In witness whereof, I hereunto subscribe my name.

ERNEST E. YAXLEY.
